United States Patent Office

Des. 196,507
Patented Oct. 8, 1963

196,507

VOLTAGE TESTER HOUSING

Dean Oehlerking and Thomas E. Trethewey, Sycamore,
Ill., assignors to Ideal Industries, Inc., Sycamore, Ill.,
a corporation of Delaware

Filed Mar. 18, 1963, Ser. No. 74,028

Term of patent 14 years

(Cl. D26—1)

FIGURE 1 is a front elevational view of a voltage tester housing, showing our new design;

FIGURE 2 is a back view thereof;

FIGURE 3 is a top view thereof;

FIGURE 4 is a bottom view thereof;

FIGURE 5 is a left side view of FIGURE 1; and

FIGURE 6 is a right side view of FIGURE 1.

We claim:

The ornamental design for a voltage tester housing, as shown.
